GAME APPARATUS

Frederick J. Marco, Chicago, Ill., assignor to Fred C. McClellan, Chicago, Ill.

Application April 25, 1935, Serial No. 18,178

5 Claims. (Cl. 273—119)

This invention relates to a game apparatus.

It is an object of this invention to provide an improved game apparatus which is relatively simple and inexpensive in construction and efficient in use.

Another object of the present invention is to provide a novel and improved device for controlling the path or direction of travel of a ball played onto the ball playing surface of the apparatus into engagement with a resilient rebound member and reprojected therefrom over the playing surface of the apparatus.

A further object of the present invention is to provide an adjustable device for causing a ball played onto the playing surface of the application to rebound thereover at a preselected angle.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a fragmentary top plan view of a game apparatus embodying a preferred form of the present invention;

Fig. 2 is a side elevational detail view of one of the resilient rebound or ball-deflecting members embodied in the invention;

Fig. 3 is a top plan view of the resilient ball-deflecting element shown in Fig. 2;

Fig. 4 is an elevational detail view of the rebound element shown in Figs. 2 and 3; and

Figs. 5, 6 and 7 are detail views of a modified form of the invention.

A game apparatus embodying a preferred form of the present invention is shown in the drawing, is therein generally indicated at 10, and comprises a cabinet 11, which includes an inclined playing board 12. Arranged in the cabinet 11 adjacent one side of the inclined playing board 12 is a ball ramp or runway 13 and arranged at the lower end of the ramp or runway 13 is a ball-propelling device or plunger 14 by means of which balls may be propelled, one at a time, onto the upper portion of the inclined playing board 12 so that they may gravitate thereover.

Slidably mounted in supporting brackets 15 which are mounted upon the inclined playing board 12, adjacent the opposite side of the latter from the ramp 13, is a rod 16 which has a handle portion 17 disposed exteriorly of the cabinet 11, the rod 16 being slidably mounted in the lower end wall 18 of the cabinet.

Mounted upon the slide rod 16 at spaced in-

tervals axially therealong and radially there-around are pins or laterally projecting elements or stop members 19.

Mounted upon each of the supporting brackets 15 is a laterally projecting pin or bolt 20 and 5 swingingly mounted upon each of these pins or bolts 20 is a wire coil 21, each of these coils 21 having a ball-reprojecting arm 22 and each of these arms 22 having a laterally projecting end portion 23.

Mounted upon each of the brackets 15, as at 42, 10 is a resilient wire member 24, each of these members 24 having an end portion 43, and these end portions 43 extend behind the swinging members 22—23 (Fig. 4). Carried by the rod 16 is an indicator 25 (Fig. 1).

By manipulating the shaft 16, through the medium of its handle 17, the player may position any preselected one of the pins 19 carried thereby in the path of rebound of the corresponding resilient member 22—23, as shown in full lines, 20 Fig. 2, so as to rebound or direct a played ball 26 from any preselected one of the ball-reprojecting resilient members 22—23 toward a preselected point or object upon the inclined playing board 25 12. This may be accomplished as follows: The player rotates the knob 17 and shaft 16 until the indicator 25 thereon indicates to the player the particular rebound or reprojecting member 22—23 against which he intends the played ball to strike. 30

The stop pins 19 on the slide rod 16 are normally disposed in an upright or vertical position, as in dotted lines, Fig. 2, out of the path of swinging movement of the reprojecting members 22—23, and when in this position the ball-reprojecting members 22—23 will, when struck by a played ball 26, swing freely about their horizontal axes or supporting bolts 20. However, by rotating the shaft 16—17 the player may move any preselected one of the laterally projecting elements or pins 19 into a horizontal position, as in full lines, Fig. 2, thereby moving the selected pin 19 into a position wherein the same will be engaged by the corresponding resilient ball-deflecting or reprojecting member 22—23 when 40 the latter is struck or engaged by a played ball 26, thereby preventing the struck ball-deflecting or reprojecting member 22—23 from swinging about its supporting axis 20 and causing the same to engage the corresponding selected stop pin 19; thereby causing the momentum of the played ball to exert a bending stress upon the resilient rebound member 22—23 and thus causing the played ball to be deflected or reprojected therefrom at a preselected angle over the in- 55

clined playing board 12 and at a preselected point thereon.

The resilient or wire members 24-43 urge the resilient ball-deflecting or reprojecting members 5 22-23 against the stop pins 19, when the latter are in effective or horizontal position, it being noted that the end portions 43 of the wire members 24 project laterally across the reprojecting members 22-23 on the opposite sides of the same 10 from the side on which the stop pins 19 are disposed when in effective position, (Fig. 4). These members 24 thus prevent a free rebound swinging movement of the reprojecting members 22-23 when the latter are engaged by the played 15 balls 26 and thus increase the effectiveness of the reprojecting or rebound movement imparted to the reprojecting members 24 when the latter are engaged by the played balls.

A modified form of the invention is shown in 20 Figs. 5, 6 and 7, and in this form of the invention the slidable operating rod 27, which corresponds to the slide rod 16 in the preferred form of the invention shown in Figs. 1 to 4 inclusive, is provided with a handle 28 which is disposed 25 exteriorly of the cabinet 29, and arranged upon this slide rod 27, at spaced intervals axially therealong and radially therearound, are laterally projecting elements or pins 30, which correspond to the stop pins 19. The slide rod 27 is slidably 30 mounted in the cabinet 29 and in a supporting bracket 32 and is normally disposed in its initial or ineffective position, as in dotted line, Fig. 5, by action of its resetting spring 44.

Mounted in the cabinet 29, above the inclined 35 playing board 31, are supporting brackets 32 and projecting laterally from each of these brackets 32 is a supporting pin 33. Attached to each of these supporting pins 33 is a coil spring 34. Each 40 of these coil springs 34 is attached at one end to a looped end portion 35 of a resilient wire ball-reprojecting member 37, and these resilient wire members 37 are swingingly mounted upon bolts 38 which extend horizontally from the brackets 32.

45 In the use of the modified form of the invention shown in Figs. 5, 6 and 7, the player may move any preselected one of the rebound members 36 from its normal or ineffective position, as in dotted lines, Fig. 7, into its effective or ball-engaging and reprojecting position, as in 50 ball-engageable and reprojecting position, as in full lines, Fig. 7, by pushing the slide rod 27 inwardly against the action of its resetting spring 44 (left to right, Fig. 5) thereby causing the corresponding and preselected pin 30 carried 55 thereby to engage under the U-shaped central portion 45 of the corresponding resilient member 36, whereupon the player may, by rotating the slide rod 27 a predetermined circumferential distance, pivot the selected rebound or reprojecting member clockwise from its normal or ineffective 60 position, as in dotted lines, Fig. 7, into its effective position as in full lines, Fig. 7. During this movement the spring 34 is moved from dotted to full line position, Fig. 7, thereby urging the 65 horizontally extending position 37 of the member 36 against the corresponding pin 39 and into the path of a ball 40 traveling over the inclined playing board 31; it being noted that when in its normal or ineffective position the resilient member 36-37 bears against a stop pin 41 which projects from the supporting bracket 32, and upon its effective position, the resilient member 70 75 36-37 abuts a stop pin 39 which also projects from the bracket 32.

75 In order to reset the ball-reprojecting mem-

ber 36-37 back into its initial position the player releases pressure applied to the slide rod 27, whereupon the resetting spring 44 returns the slide rod 27 and the pins 30 carried thereby back into their initial position (right to left, from full to dotted line position, Fig. 5), whereupon the spring 34 acts upon the selected rebound or reprojecting member 36-37 to swing the latter (counter-clockwise, from full to dotted line position, Fig. 7), thus moving the rebound member 36-37 back into its initial or ineffective position, as in dotted lines, Fig. 7.

While only one pin 30 and one set of associated devices have been shown, it is to be understood that any desired number of the pins 30 15 may be arranged upon the slide rod 27 and arranged at spaced intervals or axially therealong and radially therearound, after the manner shown and described for the arrangement of the stop pins 19 on the slide rod 16.

20 While I have illustrated and described the preferred form of construction for carrying my invention into effect, this is capable of variation and modification, without departing from the spirit of the invention. I, therefore, do not wish 25 to be limited to the precise details of construction set forth, but desire to avail myself of such variations and modifications as come within the scope of the appended claims.

Having thus described my invention what I 30 claim as new and desire to protect by Letters Patent is:

1. In a game apparatus having a member providing a ball playing surface; a plurality of ball-deflecting members mounted in said cabinet for movement into and out of position to be engaged by balls traveling over said playing surface; and means for selectively moving said ball-deflecting members into and out of position to be engaged by balls traveling over said playing surface; said means including a member slidably mounted in said cabinet for movement relative to said playing surface; and a plurality of laterally projecting elements carried by said slidably mounted member and selectively engageable with said ball-deflecting members to move the latter into effective or ball-deflecting position.

2. In a game apparatus, having a member providing a ball playing surface; a resilient ball-deflecting member movably mounted in said cabinet for movement into and out of position to be engaged by a ball traveling over said playing surface; and means for moving said ball-deflecting member into and out of position to be engaged by a ball traveling over said playing surface; said means including a member slidably mounted in said cabinet for movement relative to said playing surface and having a member thereon projecting laterally from and coacting with said ball-deflecting member to move the latter into effective position to be engaged by a ball traveling over said playing surface.

3. In a game apparatus including a cabinet having a member providing a ball playing surface; a resilient ball-deflecting member movably mounted in said cabinet for movement into and out of position to be engaged by a ball traveling over said playing surface; and means for moving said ball-deflecting member into and out of position to be engaged by a ball traveling over 70 said playing surface; said means including a member slidably mounted in said cabinet for movement relative to said playing surface and having a pin thereon projecting laterally and coacting with said ball-deflecting member to 75

move the latter into effective position to be engaged by a ball traveling over said playing surface.

4. In a game apparatus including a cabinet having a member providing a ball playing surface; a plurality of ball-deflecting members movably mounted in said cabinet for movement into and out of position to be engaged by balls traveling over said playing surface; and means for selectively moving said ball-deflecting members into and out of position to be engaged by balls traveling over said playing surface; said means including a member slidably and rotatably mounted in said cabinet for movement relative to said playing surface; and a plurality of laterally projecting members carried by said slidably mounted member and arranged at spaced intervals axially therealong and radially therearound and selectively engageable with said ball-deflecting members to move the latter into effective position to be engaged by balls traveling over said playing surface.

5. In a game apparatus including a cabinet having a member providing a ball playing surface; a plurality of resilient ball-deflecting members movably mounted in said cabinet for movement into and out of position to be engaged by balls traveling over said playing surface; and means for selectively moving said resilient ball-deflecting members into and out of position to be engaged by balls traveling over said playing surface; said means including a member slidably and rotatably mounted in said cabinet for movement relative to said playing surface; and a plurality of laterally projecting members carried by said slidably mounted member and arranged at spaced intervals axially therealong and radially therearound and selectively engageable with said resilient ball-deflecting members to move the latter into effective position to be engaged by balls traveling over said playing surface. 5
